UNITED STATES PATENT OFFICE.

ALBERT WARD PATTISON, OF LOCKPORT, NEW YORK.

BURNER.

Application filed August 6, 1921. Serial No. 490,342.

To all whom it may concern:

Be it known that I, ALBERT WARD PATTISON, a citizen of the United States, residing in the city of Lockport, in the county of 5 Niagara, in the State of New York, have invented certain new and useful Improvements in a Burner, of which the following is a specification.

This invention relates to hydrocarbon 10 burners and its principal object is to provide an economical burner of a type suitable for domestic use, and of such improved construction as to practically eliminate the usual difficulties encountered under domestic 15 conditions, such as the danger of explosion, smells from burning oil, carbon deposits which clog up and insulate heating surfaces or complicated mechanism which cannot be operated by any one but persons 20 familiar with mechanics.

Other more specific objects of the invention, as well as the construction and arrangement of parts constituting the embodiment herein disclosed will be more readily 25 understood from the following description and accompanying drawings, in which latter:

Fig. 1 is a side elevation of my improved burner with parts broken away.

Fig. 2 is a plan view partly in section.

Fig. 3 is a vertical sectional view of a part of the burner.

Fig. 4 is a transverse sectional view of the base plate, and

Fig. 5 is a view of a detail.

In these drawings, the numeral 1 designates a rectangular base plate provided with an upstanding marginal flange 2 extending entirely around the edges of the plate and 40 the sides of said flange are formed with intermediate portions 3 of less height than the remainder of the flange. At each corner of the plate and within the marginal flange 2 there is provided an aperture 4 surrounded 45 by an upstanding ring shaped wall 5, of which the flange 2 may be said to constitute a part and each wall 5 forms a socket in which is inserted the lower end of one of a plurality of air conduits 6. The conduits 6 are arched upwardly and inwardly, as shown, and converge toward an integral central portion 7, overlying the center of the base plate 1 and provided with a bottom opening 8. The base plate is further pro-

vided with a central upstanding circular 55 flange 9 integrally connected to the side portions of the flange 2 by the webs 10 and 11. The web 11 is of greater height than the web 10 and is provided with a relatively large bore 12 through which the water supply pipe is adapted to be passed, as will be later understood. The web 10 is provided with a smaller bore 13, which serves as an overflow outlet for surplus oil entrapped between the flanges 2 and 9. 65

A circular marginal wall or casing designated generally by the numeral 14 is adapted to be removably supported on the base plate within the confines of the flange 9 and said casing comprises top and bottom plates 70 designated 15 and 16 respectively. The bottom wall 16 of this casing is provided with a central threaded opening 18 in which is screwed the enlarged lower end 19 of an oil pipe or nozzle 20. Said end 19 is internally threaded for engagement with a threaded nipple 19' secured in an opening 19'', formed in the base. The upper end of the nozzle 20 projects upwardly through an opening 21 in the lower wall 15, and is of 75 smaller diameter than said opening, so as to provide an intervening passageway. The opening 21 leads from the interior of the casing 14 to the substantially frusto conical mixing chamber 22 above said opening. 80 This chamber is open at its upper end and is provided with a shoulder 23 surrounded by an annular flange 24. A plate 25 partially closes the upper end of this chamber and is provided with a central aperture 26 and 85 adjacent its periphery with a depending flange 27, which is supported upon the shoulder 23 and engages the inner side of the flange 24. The plate 25 is integrally provided on its upper surface with four equidistantly spaced ribs 28 having upwardly projecting tongues 29 entering suitable openings 30 provided therefor in a spreader plate 31, the plate being supported by the ribs. A headed bolt 32 passes downwardly through 90 the central portion of the spreader plate 31 and has mounted thereon beneath said plate two seats of mixing vanes designated at 33, and 34, respectively. It will be noted that the vanes of the upper set being located in 95 the widest portion of the mixing chamber 22 are made longer than the vanes of the lower set, in each instance, the vanes radiate

from a central hub portion 36 encircling the bolt 32. The hubs 36 are spaced apart by a short sleeve 37, the lower vane is supported by the nuts 38. Encircling the upper end of the mixing chamber 22 are a pair of superimposed water coils or steam generating chambers 39 and 40. The upper coil or generating chamber 39 is provided with a pair of outwardly and downwardly extending ears 41 formed integral therewith, and elbows connected to the upper ends of a pair of vertical pipes 42. The lower ends of said vertical pipes are connected by nipples 43, to the outer ends of a pair of horizontal pipes 44. The inner ends of pipes 44 are in turn connected to extensions 45 formed integral with the upper wall 15 of the casing 14. The lower coil or generating chamber 40 is suspended from the upper chamber 39 by means of the conduits 46, which establish communication between the two chambers. The conduits 46 are diametrically opposite each other and spaced apart from the ears 41. This lower coil or generating chamber 40 is provided with a pair of water inlets as indicated at 47, and when disposing the casing 14 within the flange 9, one of these inlets is plugged and the other is disposed above the bore 12 of the web 11, so as to be conveniently secured to a water supply pipe 48 extending upwardly through said bore. The numeral 49 indicates a pilot burner of conventional construction.

35 In the operation of the burner, oil is fed by gravity to the nozzle 20 through the central opening 19" and the nipple 19' and passes through said nozzle into the mixing chamber 22. Water is supplied to the lower generating chamber 40 and is discharged from the upper generating chamber 39 in the form of steam which is conducted to the casing 14 and passes from said casing into the mixing chamber 22 through the passageway provided between the wall of the opening 21 and the nipple 20. The passage of the steam into the mixing chamber 22 around the nozzle acts by suction to draw the oil through said nozzle and during passage of the oil and steam toward the upper end of the mixing chamber, the vanes 33 and 34 located in said chamber cause the oil and steam to become thoroughly mixed before being discharged outwardly through the openings provided between the ribs 28. The mixture is ignited as it is discharged from the mixing chamber, the plate serving to spread the flame, and combustion of the same being aided by air conveyed through the conduit 6 and discharged through the opening 8, which opening, it will be noticed is located immediately adjacent the point of combustion. The heat developed by the combustion of the gas serves to convert the water in the chamber 39 into steam which is

subsequently mixed with the oil in forming the combustible gas.

While I have disclosed in detail what I now consider to be the preferred embodiment of my invention, it is to be understood that I do not limit myself to the exact construction or arrangement of parts set forth, but that I reserve the right to resort to such changes and modifications as come within the scope of the appended claims, and do not depart from the spirit of the invention.

What is claimed is:

1. A hydrocarbon burner comprising a mixing chamber having a discharge opening for the gas generated therein, upper and lower intercommunicating hollow rings arranged to be heated by the combustion of the gas as it issues from said mixing chamber, an oil supply pipe discharging into said mixing chamber, means for supplying water to the lower ring and means for conveying steam from the upper ring to the mixing chamber to mix with said oil and thereby form the combustible gas.

2. A hydrocarbon burner comprising superimposed steam generating chambers connected by conduits extending therebetween an underlying casing a mixing chamber extending upwardly from said casing in communication therewith and having a discharge orifice disposed adjacent said generating chambers, whereby the heat produced by the combustion of gas issuing from said discharge opening is utilized to heat the generating chambers, means for introducing oil into said mixing chamber, means for supplying water to the lower generating chamber, conduits for conducting steam from the upper generator chamber to the underlying casing for delivery to the mixing chamber where it mixes with the oil to form a combustible gas, said conduits serving as the supporting means for the generating chambers, and air conduits for conveying air to the point of combustion.

3. A hydrocarbon burner comprising a water chamber, a mixing chamber having its upper end open, conduit means extending between said water chamber and mixing chamber, means for introducing oil into the mixing chamber, an apertured plate partially closing the upper end of said mixing chamber, spaced ribs on the upper surface of said plate, a spreader plate supported by said ribs, mixing vanes suspended from said spreader plate, and air conduits for conveying air to the point of combustion.

4. A hydrocarbon burner comprising a mixing chamber, having an open upper end, a centrally apertured plate partially closing said end, a spreader plate disposed above the aperture of said closing plate and supported from the latter, mixing vanes disposed in said chamber, means for introducing oil and steam into the lower end of said chamber to

form a combustible mixture, and means for supplying air to aid the combustion of the gas.

5. In a hydrocarbon burner, the combination of a vertically disposed mixing chamber open at its upper and lower ends, means for introducing oil and steam into the chamber through the lower open end thereof, a spreader supported above the upper open 10 end of the chamber, and a plurality of rotatable mixing vanes suspended from the spreader.

6. In a hydrocarbon burner the combination of a vertically disposed mixing chamber open at its upper and lower ends, means for introducing oil and steam into the mixing chamber through the lower end thereof, a perforated plate partially closing the upper end of said chamber, spaced ribs projecting from the upper surface of said plate;

a spreader supported by said ribs, and a plurality of rotatable mixing vanes suspended from the spreader.

7. A hydrocarbon burner, comprising upper and lower hollow rings connected by 25 conduits extending therebetween, a vertically disposed mixing chamber encircled by said lower ring, a perforated plate partially closing the upper end of said chamber, a spreader supported by and above said plate, 30 rotatable mixing vanes mounted in the chamber below said spreader, means for supplying water to the lower ring, means for conducting steam from the upper ring into the lower portion of said chamber and means 35 for supplying oil to the chamber to mix with the steam therein.

In testimony whereof I hereunto affix my signature.

ALBERT WARD PATTISON.
